UNITED STATES PATENT OFFICE.

CEPHAS V. FITE, OF CHARLOTTE, NORTH CAROLINA.

INTERNAL-COMBUSTION ENGINE.

1,040,299.

Specification of Letters Patent.

Patented Oct. 8, 1912.

Application filed November 14, 1910. Serial No. 592,278.

To all whom it may concern:

Be it known that I, CEPHAS V. FITE, a citizen of the United States, residing at Charlotte, in the county of Mecklenburg and State of North Carolina, have invented a new and useful Internal-Combustion Engine, of which the following is a specification.

This invention has relation to internal combustion engines of the hydro-carbon type and consists in the novel construction and arrangement of parts hereinafter shown and described.

The object of the invention is to so construct and arrange the parts of an engine of the character described that it is impossible to back fire a charge of fuel into the carburetor or other source of supply and with this object in view the structure includes a cylinder having at one end a combustion chamber and at its other end a pumping chamber. A fuel supply pipe is connected with the pumping chamber and an exhaust pipe is connected with the combustion chamber, a passageway is provided for conducting fuel from the pumping chamber to the combustion chamber and means is provided for compressing the fuel in said passageway. A double-headed piston is arranged to reciprocate in the cylinder and one of the heads thereof operates within the combustion chamber while the other head operates within the pumping chamber. The piston is provided in the vicinity of one end with a by-pass which when opposite the intake port of the pumping chamber establishes communication between the said port and the interior of the pumping chamber. The said piston is provided in the vicinity of its other end with a by-pass which when opposite the end of the fuel passageway between the said chambers is adapted to establish communication through the said passageway and the pumping chamber.

In the accompanying drawing:—Figure 1 is a vertical sectional view of the engine. Fig. 2 is a vertical sectional view of a portion of the same cut on the line 2—2 of Fig. 1. Fig. 3 is a horizontal sectional view of the same cut on the line 3—3 of Fig. 1. Fig. 4 is a horizontal sectional view of the same cut on the line 4—4 of Fig. 1. Fig. 5 is a horizontal sectional view of the same cut on the line 5—5 of Fig. 1.

The engine consists of a cylinder 1 having at one end a combustion chamber 2 and at its other end a pumping chamber 3. A water jacket 4 surrounds the major portion of the combustion chamber 2 in the usual manner and the cylinder 1 is provided with a port 5 which enters the combustion chamber and is adapted to receive a spark plug or its equivalent. A crank casing 6 is secured to the lower end of the cylinder 1 and a crank shaft 7 is journaled in the said crank casing and is provided with a crank 8. An intake port 8' communicates with the upper end of the pumping chamber when the said port is uncovered by the piston as will be explained hereinafter and an exhaust port 9 communicates with the lower end of the combustion chamber 2. The cylinder 1 is provided with a transfer passageway 10 which when uncovered has one end in communication with the combustion chamber 2 and the other end in communication with the pumping chamber 3. A sieve or screen 11 is located in the transfer passageway 10 and extends transversely across the same and through which the mixture must pass twice while it is passing through said transfer passageway. A compression piston 12 is mounted for reciprocation in the transfer passageway 10 and any suitable means may be provided for operating the said piston in order to compress the fuel mixture as it is passing through the said transfer passageway and while it is located in the same, but in order to impart to the piston 12 a proper reciprocatory movement, its rod 12' has surrounding it exteriorly of its casing, a spring 12", which normally holds the piston outwardly as illustrated in Fig. 1, the piston being moved inwardly against the tension of the spring by means of the cam 20 carried by the crank shaft 8. This cam 20 imparts an outward movement to the cylindrical rod 21 mounted in the stuffing box 22 of the crank case, the roller 23 upon the inner end thereof being at all times held in engagement with the cam 20. The outer end 24 of the rod 21 is operably connected at the lower end with the lever 25, which is fulcrumed at the end of the arm or bracket 26, while the outer end of the piston 12' is operably connected as at 27 to the upper end of the lever 25. By this means it will be seen that the rotation of the crank shaft and the cam 20 will impart an inward

movement to the piston 12, while the spring 12" will impart the opposite movement, thus properly reciprocating the piston 12.

5 A piston rod 13 is connected with the piston 14 and also with the crank 8 in the usual manner. The piston 14 is mounted for reciprocation in the cylinder 1 and is provided at one end with a head 15 adapted to operate in the combustion chamber 2 and at 10 its other end with a head 16 adapted to operate in the pumping chamber 3. The piston 14 is provided in the vicinity of its upper end and near the head 15 with a by-pass 17 which when in register with the induction port 8 establishes communication between said port and the interior of the pumping chamber 3 whereby the fuel mixture may be admitted from the said induction port into the said pumping chamber. This occurs 15 when the piston 14 is in its lowermost position in the cylinder 1. The piston 14 is also provided in the vicinity of the head 16 with a by-pass 18 which is adapted to register with one end of the transfer passage-way 10 and when in such registration establishes communication between the pumping chamber 3 and the said transfer passageway. The parts of the engine are so arranged and the piston 14 is of such length that 20 when it is in its lowermost position in the cylinder 1 it uncovers the exhaust port 9 and also uncovers that end of the transfer passageway 10 which communicates with the combustion chamber 2. The piston 14 is provided upon its upper end with a baffle plate 19 as is usual in engines of this type.

The operation of the engine is as follows: Presuming that the piston 14 is descending and is about to assume its lowermost position as illustrated in Fig. 1 of the drawing and the by-pass 17 is over the inner end of the induction port 8. This establishes communication between the induction port 8 and the pumping chamber 3 and as the said 40 piston descends and assumes the position as shown in Fig. 1 the mixture is drawn into the pumping chamber 3 through the said by-pass 17 and the induction port 8. At the same time the upper end of the piston 14 passes below the exhaust port 9 and below the upper end of the transfer passage 10. Thus the burnt gases in the combustion chamber 2 may scavenge through the exhaust port 9. Upon the upward stroke of 45 the piston 14 the by-pass 17 passes above the induction port 8 and the side of the piston 14 closes the said induction port 8. When this is done the mixture is trapped for a short period of time in the pumping 50 chamber 3 and subjected to compression. However when the upper end of the by-pass 18 registers with the lower end of the transfer passage 10 the said compressed fuel is forced by the head 16 into the transfer passage 10. Thus the fuel is forced from

the pumping chamber 3 into the said transfer passage. While in the transfer passage the piston 12 advances and subjects the fuel to further compression at the time the piston 14 begins to descend, thus the said fuel is held trapped in the transfer passage 10 and as soon as the upper end of the piston 14 passes below the upper end of the said transfer passage, the compressed fuel passes into contact with the baffle plate 19 and is deflected into the upper end of the said chamber. At the same time the mixture entering the combustion chamber 2 sweeps out the burnt gases through the exhaust port 9. By reason of the fact that when the piston 14 descends and the upper end of the by-pass 18 is carried below the lower end of the transfer passage 10 the upper end of the said piston 14 is in close contact with both ends of the transfer passage 10 and thus during the time that the explosion takes place in the combustion chamber 2 it is impossible for any of the burnt gases to pass down through the transfer passage 10 into the pumping chamber 3 and through the induction port 8 into the carburetor or other source of feed. Thus it is evident that back firing is effectually and positively prevented, by reason of the fact that as the sieve or perforated material 11 is located transversely across the transfer passage 10 and it is therefore impossible for unconsumed products of combustion to pass in such condition into the inlet portion of the said transfer passage. This eliminates the possibility of premature explosion in the said transfer passage. Any suitable mechanical means may be provided for operating the compression piston 12 from the shaft 7 of the engine but as such connecting means are common expedients and form no parts of the present invention they are not illustrated or described herein.

Having thus described the invention 110 what I claim as new and desire to secure by Letters Patent is:—

1. An internal combustion engine comprising a cylinder provided with a combustion chamber and a pumping chamber, said combustion chamber having an exhaust port and said pumping chamber having an induction port, a transfer passageway adapted to lead the mixture from the pumping chamber into the combustion chamber, a compression piston operatively mounted in said transfer passageway, a piston mounted for reciprocation in the cylinder and having a head operating in the combustion chamber and a head operating in the pumping chamber said piston being provided in its side with a by-pass which when in register with the induction port establishes communication between the said port and the pumping chamber, said piston also having 130

in its side a by-pass which when in register with the transfer passage establishes communication between the said passage and the pumping chamber.

5 2. An internal combustion engine comprising a cylinder provided with a combustion chamber and a pumping chamber, said combustion chamber having an exhaust port, said pumping chamber having an induction port, a transfer passageway adapted to lead the mixture from the pumping chamber into the combustion chamber, a screen extending transversely across said transfer passage and through which the said mixture is compelled to pass in traveling through the said passage, a compression means mounted for operation in the transfer passageway, a piston mounted for reciprocation in the cylinder and provided with a head which oper-

ates in the combustion chamber and provided with a head which operates in the pumping chamber, said piston having a by-pass which when in register with the induction port establishes communication between said port and the interior of the pumping chamber, said piston also having a by-pass which when in register with the transfer passageway establishes communication between the said passageway and the interior of the pumping chamber.

30

In testimony that I claim the foregoing as my own, I have hereunto affixed my signature in the presence of two witnesses.
